MOUNTING FOR ELECTRON TUBES

Tom L. Yates, Erie, Pa., assignor to Lord Manufacturing Company, Erie, Pa., a corporation of Pennsylvania

Application February 19, 1944, Serial No. 523,015

3 Claims. (Cl. 248—358)

The invention relates to flexible mountings for isolating electron tubes from vibrations.

The invention provides an electron tube mounting having a plate that is formed for attachment to a panel or other support, and having one or more rings formed for receiving electron tube sockets. Each ring is connected to the plate by vibration-isolating bodies of resilient material such as rubber, and the ring and plate are provided with abutments which are arranged in cooperating pairs the members of which are normally spaced from each other to permit limited relative movements between the plate and ring. The abutments are so formed that they engage each other to limit the movement of the ring when a tube is pressed into or removed from a socket that is borne by the ring.

The invention is illustrated in the accompanying drawing of which Fig. 1 is a plan view of the mounting to enlarged scale; Fig. 2 a transverse sectional view taken on the line II—II of Fig. 1; Figs. 3 and 4 detail sectional views taken on the lines III—III and IV—IV, respectively, of Fig. 1; and Fig. 5 a side view of the mounting to reduced scale, the mounting having assembled with it an electron tube positioned in a socket that is connected to the mounting.

The mounting shown in the drawing is for a single electron tube, and for that purpose it comprises a plate 1 having a pair of lugs that are provided with holes 2 for connecting it to a panel or other support, and having a single circular opening 3. Within this opening there is an inner plate or ring 4 which is provided with a central circular opening 5 and is formed to hold a tube socket. To such end, ring 4 is provided with an inwardly projecting lug 5a for properly positioning a socket which is held on the ring by a snap ring in the usual manner.

Ring 4 is connected to plate 1 by plurality of bodies 10 of resilient material such as soft rubber which are U-shaped to afford the requisite sensitivity and softness in directions perpendicular and parallel to plate 1 and in intermediate positions. Four bodies of rubber 10 are shown extending between plate 1 and ring 4 at equal annular intervals, each being provided with laterally extending flanges which are bonded or otherwise suitably connected to the plate and ring. When the ring is so connected to plate 1 it is freely movable with relation to the plate.

At opposite sides of its opening 3 plate 1 is provided with two abutment lugs 11 which are struck upwardly from the plate and inwardly of the wall of the opening, as shown in Fig. 2.

These lugs are positioned between the adjacent ends of adjacent pairs of rubber bodies 10, and similar lugs 12 are struck downwardly from ring 4 and extend outwardly beneath lugs 11, as also shown in Fig. 2. Disposed at right angles to the pairs of cooperating lugs 11 and 12, plate 1 is provided with downwardly and inwardly extending lugs 13, and ring 4 with upwardly and outwardly extending lugs 14, as shown in Fig. 4, which lugs are also arranged between the adjacent ends of rubber bodies 10 and cooperate in pairs.

In Fig. 5 the mounting is shown as being equipped with a socket 20 in which an electron tube 21 is mounted. When pulling the tube upwardly to remove it from socket 20, the frictional resistance to such removal causes ring 4 to move upwardly as viewed in Figs. 2 and 5 until lugs 12 engage lugs 11 which limit the upward movement of the ring. Similarly, when pressing a tube into the socket ring 4 moves downwardly as viewed in Figs. 2 and 5 until lugs 14 engage lugs 13 of plate 1. By thus limiting the relative movements of ring 4 and plate 1 the soft rubber mountings 10 and their attachments to plate 1 and ring 4 are not broken or otherwise impaired.

What I claim as new is:

1. A mounting for electron tubes, comprising a plate formed for attachment to a support and provided with an opening, a socket-receiving ring movably positioned within said opening, and vibration-isolating bodies of resilient material such as rubber spaced angularly around said opening so adjacent ends of the bodies are circumferentially spaced apart and connecting the ring to the plate, the ring and plate being provided with cooperating pairs of normally spaced abutments, the respective pairs being spaced apart angularly around said plate opening between said adjacent ends of said bodies, said pairs of abutments being formed to engage each other to limit movements of the ring with relation to the plate when placing a tube in and removing it from a socket borne by the ring.
2. A mounting for electron tubes, comprising a plate formed for attachment to a support and provided with an opening, a socket-receiving ring movably positioned within said opening, and arched vibration-isolating bodies of resilient material such as rubber spanning the gap between the ring and plate and connecting them to each other, the ring and plate being provided with cooperating pairs of normally spaced abutments alternately struck laterally from opposite sides of the plate and ring and formed to engage each

other to limit movements of the ring with relation to the plate when placing a tube in and removing it from a socket borne by the ring.

3. A mounting for electron tubes, comprising a plate formed for attachment to a support and provided with an opening, a socket-receiving ring movably positioned within said opening, and arched vibration-isolating bodies of resilient material such as rubber spanning the gap between the ring and plate and connecting them to each other, said bodies being spaced at substantially equal intervals angularly around said plate opening so adjacent ends of the bodies are circum-

ferentially spaced apart, the ring and plate being provided with two pairs of normally spaced abutments, the respective pairs being spaced apart angularly around said plate opening between said adjacent ends of said bodies, said pairs of abutments being formed to engage each other to limit movements of the ring with relation to the plate, one pair being effective to limit such movements when placing a tube in and the other pair for limiting such movements when removing a tube from a socket borne by the ring.

TOM L. YATES.
